CLAIM

The ornamental design for a pet waste receptacle, as shown and described.

DESCRIPTION

FIG. 1 is a perspective view of a pet waste receptacle, showing my new design;

FIG. 2 is a perspective view thereof;

FIG. 3 is a right side elevation view thereof;

FIG. 4 is a left side elevation view thereof;

FIG. 5 is a rear elevation view thereof;

FIG. 6 is a front elevation view thereof;

FIG. 7 is a top plan view thereof; and,

FIG. 8 is a bottom plan view thereof.

The broken lines in the figures illustrate portions of the pet waste receptacle that form no part of the claimed design.

1 Claim, 7 Drawing Sheets
